UNITED STATES PATENT OFFICE.

FRANK J. FARR, OF NEAR TWINING, MICHIGAN.

ATTACHMENT FOR BURNERS.

937,989.

Specification of Letters Patent.

Patented Oct. 26, 1909.

Application filed May 23, 1908. Serial No. 434,636.

To all whom it may concern:

Be it known that I, FRANK J. FARR, a citizen of the United States, residing near Twining, in the county of Arenac and State of Michigan, have invented certain new and useful Improvements in Attachments for Burners; and I do hereby declare the following to be a full, clear, and exact description of the invention, such as will enable others skilled in the art to which it appertains to make and use the same.

My invention relates to lamp attachments, one object being the provision of means for removably supporting the chimney and hood relative to the lamp burner in such manner that the chimney and hood may be tilted back from the burner to permit the lamp to be cleaned, the wick trimmed or lighted and extinguished with ease and dispatch and without burning the fingers. The flame can be blown out without smoking the chimney or hood.

Another object is the provision of means capable of being quickly engaged and disengaged relative to the chimney and hood either or both, to permit their removal.

Another object is the provision of means for releasably locking the hood in position on the burner.

A still further object is the provision of a neat, simple and inexpensive device which will greatly facilitate the lighting or cleaning of a lamp.

To these and other ends my invention consists in certain novel features and combinations of parts such as will be more fully described hereinafter and particularly set forth in the claims.

In the accompanying drawing Figure 1 is a side view of my invention partly broken away, the dotted lines showing the chimney and hood tipped back. Fig. 2 is a detail side view of the hood. Fig. 3 is a detail top plan view of the burner. Fig. 4 is a detail perspective view of the clamping collar, the hinge being shown in dotted lines and Fig. 5 is a detail perspective view of the stationary member of the hinge.

My invention is applicable to table or hanging lamps, and in the latter class of lamps the wick can be easily and quickly ignited and extinguished without taking the lamp down.

Referring to the drawings, A, indicates the gallery of any suitable burner provided

with a wick tube (1), the wick in which is raised or lowered by means of the rotary shaft (2) in any convenient manner. B, indicates the hood and C, the chimney.

In the ordinary construction heretofore on the market, the hood was hinged directly to the base of the burner which carried resilient fingers adapted to engage the lower end of the chimney and hold it releasably in position, the chimney being seated on the burner. This arrangement did not permit the chimney to be tilted with the hood. Instead the chimney had to be removed before the wick could be lighted, and then replaced. In extinguishing the flame, it was customary to lower the wick and blow down the open top of the chimney resulting in "smoking up", the chimney and hood as well as involving some little discomfort from the heat impinging against the face, as well as danger from cracking the chimney. To avoid these disadvantages, I have devised a tilting holder for the hood and chimney which will admit of free access being had to the flame without discomfort or injury to the operator or liability of breakage. The holder may be formed in any convenient manner but I have shown it as composed of wire which is both inexpensive and easily made up. The wire or other material may be tempered or not as desired. That form of holder herein shown comprises a supporting member shown in detail in Fig. 5 and consisting of a yoke (3), the free ends of which are turned down. Intermediate its ends the yoke is provided with a pair of loops or eyes (4), (4), parallel with each other and extending substantially at right angles to the arms of the yoke. This yoke is formed of one piece of wire which is bent into the two loops in such a manner that the connecting bar (5) prevents the loops from spreading apart.

The arms of the yoke are rolled, crimped or otherwise secured to the outer periphery of the burner, the loops projecting outward and upward from the burner and constituting the stationary knuckles of a hinge connection.

The remaining member of the holder comprises a split collar formed preferably of one piece of wire, and consisting of an upper annular strand (7) and a lower annular strand (6) connected at the rear by a back bone (8) of wire twisted to impart strength thereto. The lower strand (6) is extended

beyond the backbone to form a tail piece (9) of twisted wire, the tail piece being extended laterally intermediate its ends to form a cross bar (10) received in the loops or eyes (4), (4'). In this manner the collar is hinge-connected to the yoke and is capable of tilting to the position shown in dotted lines in Fig. 1, the tail piece engaging the connecting bar (5) as a stop to limit its opening movement.

The upper end of the backbone is offset slightly as shown at (11) and the strand (6) is bent into substantially U-shape at the back as at (11') so that it will not engage the chimney and also to afford more resilience to the strands (6) and (7).

The forward ends of the collar terminate in double loops (12), (12'), and (13), (13') respectively. Hooks (14), (14'), are pivotally secured to the ends of loops (12), (12'), the free ends of the hooks adapted to engage the opposite corresponding loops (13) (13') to retain the resilient collar in contracted position.

As one means for connecting the collar and hood, I provide the lower strand (6) of the collar with a plurality of inward projections (15) removably receivable in openings (16) formed in the lower flange (17) of the hood B. The strand (6) is clamped around the flange and the projections held in the openings (16) when hook (14') is in the locked position shown in Figs. 1 and 4. The hooks are provided with the finger holds (23^a) to facilitate the disengagement of the hooks from the loops (13), (13').

The lower end of the glass chimney C is seated on the shoulder (19) of the hood and embraces the wall (20) which operates to steady the chimney. The upper strand (7) is adapted to clasp the chimney snugly and hold it firmly on its seat at all times when the hook (14) is in engagement with the loop (13).

In order to prevent the accidental tilting of the chimney and hood and to retain the parts in the position shown in full lines in Fig. 1, I provide the hood B with a spring catch (21). The gallery A of the burner is recessed as at (22) and the catch is adapted to take under the recessed edge of the gallery, the recess guiding the hook to position. A finger hold (23) on the catch permits the latter to be released from the gallery. The inner end of the catch is secured inside the hood as shown by the dotted lines 21^a in Fig. 2, and the catch projects through an aperture in the flange (17) of the hood. The hood and chimney can be released from the holder for cleaning or other purposes and the burner can be easily and quickly cleaned, when the chimney and hood are removed.

Pressure against the finger hold (23) in an upward direction will release the catch

(21) and permit the chimney and hood to be tilted back when lighting or extinguishing the lamp.

When the collar is formed of wire, the tail piece (9) is first formed from the middle portion of the wire which is next bent to form the cross bar (10) after which it is once more twisted to hold the cross bar in shape. The wire is then bent to form the lower strand (6) having the projections (15), after which the wire is formed into the V-shaped loops (12), (12'), and (13), (13') respectively. The upper strand (7) of the collar is then formed and the two ends of the wire brought together and twisted to form the back bone (8), the extreme ends of the wire being spread apart and coiled around the rear of the lower strand (6) as shown.

Having thus fully disclosed my invention, what I claim as new is:—

1. In a device of the character described, the combination of a burner, a hood applied to the burner, a chimney, and a chimney engaging member hinged to the burner and formed with two independent strands, one of which engages the hood while the opposite strand engages the chimney.

2. In a device of the character described, the combination of a burner, a hood applied to the burner and formed with openings, a chimney, and a chimney engaging member hinged to the burner and formed with two independent strands, one of the strands engaging the chimney while the opposite strand is formed with projections adapted to engage the openings in the hood.

3. An attachment for lamp burners comprising a suitable support, a split collar hinged to the support, one of the free ends of the collar terminating in double loops, hooks pivotally secured to the opposite free end of the collar, the hooks removably receivable in the respective loops, the collar being adapted to embrace a hood and a chimney.

4. An attachment for lamp burners comprising a tilting split collar consisting of upper and lower strands, a backbone connecting the strands, the backbone being offset from the upper strand, a tail piece projecting rearwardly from the lower strand, a cross bar carried by the tail piece, a support having eyes, the cross bar received in the eyes of the support, the lower and upper strands being adapted to releasably engage a hood and chimney respectively.

5. In a device of the character described, the combination of a burner, a supporting member projecting from the burner and provided with oppositely disposed eyes, a hood applied to the burner, a chimney, and a laterally expandable chimney engaging member formed with a tail extending between the eyes of the supporting member and provided with means co-acting with said eyes

to form a pivotal connection between the chimney engaging member and said burner.

6. In a device of the character described, the combination of a burner, a hood applied to the burner, a yoke projecting from the burner and provided with transversely alined eyes, a chimney, and a laterally expansible chimney engaging member formed with a tail extending between said eyes and adapted to engage the hood, the tail being formed with a cross bar which is pivotally mounted in the eyes of said yoke.

7. The combination with a lamp burner having a gallery, of a U-shaped yoke secured to the gallery, the free ends of the arms of the yoke passing through the gallery, the yoke formed into a pair of eyes intermediate its ends, a connecting bar extending between the eyes, a collar having a cross bar received in the eyes, and a chimney and hood releasably clasped and wholly supported by the collar.

8. In a device of the character described, the combination of a burner, a supporting member projecting from the burner, a hood applied to the burner, a chimney, a chimney engaging member embodying two independ-

ent strands connected by a back bone, one of the said strands engaging the chimney while the opposite strand engages the hood and is formed with a tail which is pivotally mounted upon the supporting member projecting from the burner.

9. The combination with a lamp burner having a gallery, of a yoke, the arms of which are secured to the gallery, the yoke provided with a pair of upturned eyes intermediate its ends, a connecting bar for bonding the eyes together against lateral movement away from each other, a collar, a cross bar carried by the collar and received in the eyes, means carried by the collar for limiting the swinging movement thereof and for swinging the collar, a hood and a chimney both releasably engaged and wholly carried by the collar, and a catch for normally connecting the collar and burner.

In testimony whereof, I affix my signature in presence of two witnesses.

FRANK J. FARR.
